Primary Examiner — Brian N. Vinson*(74) Attorney, Agent, or Firm* — Tsircou Law, P.C.(57) **CLAIM**

We claim the ornamental design for a light assembly, as shown and described.

DESCRIPTION

FIG. 1 a perspective view of a light assembly of the new design.

FIG. 2 is a front elevational view of the light assembly of FIG. 1.

FIG. 3 is a back elevational view of the light assembly of FIG. 1.

FIG. 4 is a first side view of the light assembly of FIG. 1.

FIG. 5 is a second side view of the light assembly of FIG. 1.

FIG. 6 is a top view of the light assembly of FIG. 1; and, FIG. 7 is a bottom view of the light assembly of FIG. 1.
